UNITED STATES PATENT OFFICE.

JARVIS P. PINDER, OF JOHNSTOWN, PENNSYLVANIA.

COKE-OVEN DOOR.

Application filed April 9, 1923. Serial No. 630,869.

To all whom it may concern:

Be it known that I, JARVIS P. PINDER, a citizen of the United States, and a resident of the city of Johnstown, county of Cambria, and State of Pennsylvania, have invented certain new and useful Improvements in Coke-Oven Doors; and I do hereby declare the following to be a full, clear, and exact description of the invention, such as will enable others skilled in the art to which it appertains to make and use the same.

My invention relates to a door for coke ovens, especially those of the horizontal by-product type, and relates more particularly to the construction and arrangement of a rabbling door, or so-called chuck door forming part thereof. These rabbling doors are arranged in the upper part of the coke oven main doors and are adapted to provide small and convenient openings through which a leveling tool may be inserted for the purpose of leveling off the charge of coal after it has been dumped through the top of the oven from a coal larry or otherwise.

After the coal is dumped into the oven the top surface thereof may be irregular, and it is then leveled by the leveling tool, which tool is ordinarily mounted on the coke pusher and is inserted through the rabbling door opening. After the oven is charged with coal and the rabbling door is open, the leveling tool inserted and the coal charge leveled by the reciprocating movement thereof, and after this is done the rabbling door is closed and firmly seated in position to maintain the oven tight. Previous doors of this kind have required the use of lute, clay, etc., for sealing them, but by means of my invention and the construction thereof the necessity for this is obviated, as will be further hereinafter explained.

My construction is also of a character such that expensive machine work on the door and parts thereof is eliminated, and I am able to furnish coke oven rabbling doors and frames therefor of ordinary castings, which can easily be tightly closed and so remain without the necessity for lute, clay, etc., thereby economizing time, labor and material.

The opening of my rabbling door is shown as substantially rectangular in form, but it may be of any other shape desired, and the frame therefor is made with angular or narrow edges surrounding the exterior of the opening, and the rabbling door is made of

plug type with tapered edges adapted to fit therein and provided with a loose hinge and a yoke and a central cam arrangement, whereby it may be swung into place and then pushed firmly into the opening and held by the cam, and this can be done uniformly as the loose hinge permits the plug door to be pushed bodily into place to seat it against the frame. When this is done the sharp or narrow edges of the frame contact with the tapered edges of the plug rabbling door and form tight contact of the door and jamb, and in this respect my rabbling door is improved over other constructions, as it requires no added sealing means.

I have found that my plug door is tight and free from leakage when it and the jamb are clean, but should there be a deposit or incrustation of tar, soot or other material on the edges of the door or jamb the narrow or angular corners will cut or scrape through such deposit when the door is pushed into closed position, thus providing direct contact of the parts to form a tight closure, and in certain cases such a deposit might provide an additional seal, but such seal is really unnecessary with my construction.

The main coke oven door may be a casting without any machining, and the plug door may also be a casting without any machine work, except possibly the drilling of the hinge pin holes if desired. When constructing this door I may force the plug door into position against the jamb, and then by means of a blunt nosed calking tool or otherwise, force the metal of the door jamb against the door so that in spite of the rough castings the edges of the jamb conform to the outline of the tapered plug, so that afterwards whenever the door is put in place it fits substantially tight in all parts and prevents leakage from the oven.

As compared with rabbling doors of other constructions, which require lute, my door is quick and easy of operation, requiring no special sealing means and can be closed and locked in a few seconds, whereas other doors with which I am familiar require two or three minutes for closing and luting.

As the gases which are first distilled after charging the oven are the most valuable, this quick action of my rabbling door results in saving these valuable gases, a portion of which would otherwise be lost.

Having thus given a general description

of my invention, I will now, in order to make the matter more clear, refer to the annexed sheet of drawings, which form part of this specification, and in which like characters refer to like parts:—

Figure 1 is a front elevation of a coke oven door with my improved rabbling door at the upper portion thereof; Figure 2 is a vertical longitudinal sectional elevation taken on the line II—II of Figure 1; Figure 3 is an end elevation of the yoke and the cam pivoted thereto; Figure 4 is a side elevation of the yoke and cam, and Figure 5 is a transverse sectional elevation taken on the line V—V of Figure 1.

Referring now to the characters of reference on the drawings:—1 is the jamb wall of an oven having channel binders or buckstays as illustrated, which is shown of form 20 adapted to receive a coke oven door of the type shown, but these main jambs may be of any form desired to receive any type of main oven door that may be desired; 2 is the body of the coking chamber of the oven; 25 3 are the inclined portions of the jamb walls thereof; 4 is the main coke oven door having side portions 5, a bottom flange 6, a top flange 7, edge flanges or sides 8, while 9 are the vertical exterior flanges of the door 30 connected by the cross flanges 10, which are adapted to stiffen and strengthen the door and aid in cooling thereof by exposure to the outer air. The vertical flanges 9 are provided with reinforcing ribs 11, and 12 is an 35 opening in the bottom of the main door which is filled with bricks 13, which may be removed when desired for the purpose of introducing gas pipes, etc., when starting up the oven, after which the opening is closed by the 40 bricks 13. The main door is provided with brick or refractory lining 14 and has a rabbling door opening 15 near its upper end. This rabbling door opening 15 is provided with boundaries or jambs 16, the edges of 45 which are arranged at an angle or substantially narrow or sharp as shown, adapted to receive the plug-shaped rabbling door 17. This rabbling door has tapered or beveled edges 18 and a refractory lining 19. This 50 rabbling door is provided with hinge lugs 20, adapted to co-operate and register with the stationary lugs 21, forming part of the main door, and are pivoted thereto by the hinge bolt or pin 22 as illustrated, so that 55 the door may be swung to open or closed position. The hinge pin holes 38 in the hinge lugs 21 of the main door are oval or larger than the hinge pin 22, or the hole in the hinge lug 20 of the plug door 17 may 60 be larger to allow the plug door to be moved bodily by the cam 33 when seating it against its jamb. The rabbling door 17 has a central rib 23 provided with outstanding flanges 24, to which a wear plate 25 is secured by 65 means of the bolts 26. The plug door it-

self may preferably be made of cast iron, while the wearing plate may be made of hard steel, and is removable, and may easily be lined up, shimmed or replaced when the parts are so worn that the cam 33, which 70 contacts with it, will firmly push the rabbling door into the position illustrated in Figures 1, 2 and 5. Reinforcing ribs 27 are provided to strengthen the rabbling door as illustrated. In order to close the door I 75 provide a yoke 28 formed with a slot 29 in the central portion thereof, the ends being provided with eyes or perforated end portions 30 adapted to project between the corresponding lugs or ears 31 formed on the 80 main door adjacent to the rabbling door opening, and this yoke is pivotally attached thereto by the hinge pins 32. Mounted at the central portion of the yoke is a cam 33, which is pivoted thereon by means of the 85 bolt or pin 34, and it is provided with the outstanding lever arm 37 forming part thereof for the purpose of operating it. The main coke oven door has upper rounded 90 outstanding flanges 35 connected by a rod 95 or bar 36, which is adapted to receive the lifting or handling mechanism for the main door (not shown).

The operation of my rabbling door is as follows:—The coal having been charged into 95 the oven through the top openings thereof (not shown); if the rabbling door is closed, the cam lever 37 is first moved upwardly, thereby releasing the rabbling door 17, whereupon the yoke 28 is swung to the right 100 and the door 17 is swung to the left as indicated by broken lines in Figure 5, thereby leaving the rabbling opening 15 open for the introduction of the leveling tool. The leveling tool is then inserted through the rabbling doorway, the coal is leveled, the leveling tool withdrawn and the rabbling opening closed by swinging the tapered door 17 into the position shown in Figure 5, then 105 turning the yoke 28 over the door and then pushing the door 17 firmly into position by moving the lever 37 downwardly, thereby causing the cam 33 to contact with the door 17 and clamping it firmly in place; and this is done uniformly by reason of the loose 110 hinge pin of the plug door as before described. If the jamb 16 or the door 17 itself or the beveled edges 18 thereof are encrusted with tar, soot, or other material, this 115 forcible closure of the same against the sharp or narrow edges 16 of the doorway will cut or scrape through these deposits and cause the beveled or tapered metal edges of the door to be solidly seated against the narrow or sharp corners 16 of the door jamb. 120

Although I have described the rabbling door jamb as provided with substantially angular exterior corners surrounding the opening, these corners need not be very sharp, but might be slightly rounded or 130

provided with a slight bevel, as indicated in Figure 2 to provide a narrow bearing surface against which the plug door is seated. The corners of the jamb, however, should 5 be narrow enough so that the pressure of seating the tapered plug against the same need not be excessive to cause a tight closure of the rabbling door opening in the manner indicated.

10 Although I have shown and described my invention in considerable detail, I do not wish to be limited to the exact and specific details thereof, as shown and described, but may use such modifications in, substitutions for, or equivalents thereof as are embraced within the scope of my invention, or 15 as pointed out in the claims.

Having thus described my invention, what I claim and desire to secure my Letters Patent is:—

20 1. A coke oven door having a rabbling door opening therein, a jamb therefor, a closure for said opening comprising a plug with tapered edges adapted to contact with the 25 corners of the jamb, and means for holding said closure firmly in position.

2. A coke oven door having a rabbling door opening therein, a jamb around said opening having exterior angular corners, a 30 door therefor having tapered edges adapted to contact with the corners aforesaid, and means for firmly securing the door in position against said jamb.

3. A coke oven door having a rabbling door opening therein, a jamb therefor provided with a narrow exterior corner, a tapered plug rabbling door adapted to fit said opening with its tapered edges contacting with the said corner of said jamb, a yoke 35 secured to said coke oven door, and a cam pivoted on said yoke adapted to contact with and force and hold the rabbling door in position.

4. A coke oven door provided with a rabbling door opening therein, a jamb surrounding said opening having an exterior substantially narrow corner portion, a tapered plug door adapted to close said opening with its tapered edges contacting with the corner 45 aforesaid, a yoke secured to the coke oven door, adjacent the plug door, and pressure means on said yoke whereby the plug door may be firmly pressed to or released from its closed position.

5. A main coke oven door having a rabbling door opening therein, a jamb surrounding said opening with a substantially narrow exterior corner, a plug door with a tapering edge adapted to close said opening 55 with its edge contacting with said corner,

said plug being loosely hinged to the main coke oven door, a yoke adapted to surround said plug door with its ends pivoted to said main coke oven door, a cam mounted in said yoke, provided with a lever adapted to force 65 the plug firmly against the jamb corner to close the rabbling opening, said door being adapted to be opened by releasing the cam and swinging the yoke and door on their respective pivots.

6. A main coke oven door having a rabbling door opening therein, a jamb surrounding said opening having substantially narrow or angular corners, a plug door with tapering edge adapted to partially project 75 within said opening with its tapered edge contacting with the said corners of the jamb, said plug door being loosely hinged to the main coke oven door, a yoke adapted to partially surround said plug door with its ends 80 pivoted to said main coke oven door, a cam mounted in said yoke, provided with a lever adapted to force the plug door firmly against the jamb corners to close the rabbling opening, said plug door being adapted to be 85 opened by releasing the cam and swinging the yoke and plug door oppositely on their respective pivots.

7. A main coke oven door having a rabbling door opening therein, a jamb surrounding said opening having substantially narrow exterior corners, a plug door with tapering edges adapted to partially project 90 within said opening with its tapered edge contacting with the narrow corners of said 95 jamb, a wear plate removably secured to the outer portion of said plug door, said plug door being loosely hinged to the main coke oven door, a yoke adapted to partially surround said plug door with its ends pivoted 100 to said main coke oven door, a cam mounted in said yoke, provided with a lever, and adapted to contact with said wear plate to force the plug firmly against the jamb corners to close the rabbling opening, said plug 105 door being adapted to be opened by releasing the cam and swinging the yoke and door oppositely on their respective pivots.

8. A plug door, a frame therefor, the corners of the frame adjacent the plug being 110 calked to conform to the outline of the plug.

9. A rabbling door opening provided with a jamb, a closure for said opening comprising a plug with tapered edges adapted to contact with the corners of the jamb, said 115 jamb being calked at its corners to conform to the outline of the plug.

In witness whereof I hereunto affix my signature.

JARVIS P. PINDER.
